Inventor:

Alexander Story

UNITED STATES PATENT OFFICE.

ALEXANDER STORY, OF WASHINGTON, IOWA.

CAR-COUPING.

SPECIFICATION forming part of Letters Patent No. 275,870, dated April 17, 1883.

Application filed February 3, 1883. (No model.)

To all whom it may concern:

Be it known that I, ALEXANDER STORY, a citizen of the United States, residing at Washington, in the county of Washington and State of Iowa, have invented certain new and useful Improvements in Car-Couplings; and I do hereby declare the following to be a full, clear, and exact description of the invention, such as will enable others skilled in the art to 10 which it appertains to make and use the same.

My invention is an improvement in car-couplings so arranged that cars coming together will couple automatically. It is simple, durable, and reliable at all times.

15 It consists mainly of a bent steel spring, as shown in Figure 1, and adjusted in the draw-head as shown in Fig. 2.

In the drawings, Fig. 1 represents the bent self-adjustable steel spring A. Fig. 2 represents a longitudinal vertical section of an ordinary draw-head with flaring mouth, with the bent spring inserted.

In the upper side of the draw-head, near the front part, is a recess for the reception of the 25 end *a* of the spring, which spring is held in place by a bolt, *b*. The upper prong, *c*, of the spring presses against the upper side of the draw-head when the coupling-link is in place. The lower prong, *d*, pressing down upon the end 30 of the link, holds it in a horizontal position ready for entering the mouth of the approaching draw-head. This lower prong of the spring *a* has a hole, *e*, near the end, which, when the link is in place, is in range with the two holes 35 in the draw-head, through which the coupling-pin drops, and fastens the link. When the link is withdrawn the end of the spring drops down to the dotted line *g*, covering the lower hole in the draw-head, affording a place 40 for the coupling-pin to stand on, thus preventing it (the pin) from entering the lower hole. There is a recess, *f*, into which the spring drops when the link is withdrawn. When the link in coupling is pushed back into the draw-head it raises the end of the spring till the 45 hole in it ranges with the two holes in the draw-head, when the pin that stood on the end of the prong drops into place and the coup-

ling is done. To prevent the pin from dropping too soon, or before the end of the link 50 passes the hole, the prong is raised a little higher than the thickness of the link before the three holes are exactly in range. This is done by the point of the prong being lower than at the hole because of its inclination. On 55 either side of the upper prong there is, as seen in Fig. 2, at *i*, a projection in the sides of the draw-head, which gradually extends downward as it recedes from the mouth of the draw-head. This is intended to prevent the link as 60 it enters from striking against the lower prong of the spring and raising it too soon and dropping the pin before the link is in place or has passed beyond the pin. The lower prong is thicker than the upper one, and strengthened 65 by ridges *h* on either side of the hole, both on the upper and under side of the prong. The ridges on the under side are intended not only to strengthen the prong, but to prevent the link from striking against the edge of the hole 70 when entering. The upper hole in the draw-head is of considerable depth, and the pin fits nicely in it. This is to steady the lower end of the pin and cause it to drop readily through the lower holes.

Having thus described my invention, what 75 I claim is—

1. In a car-coupling, the draw-head provided with a recess in its upper interior wall, in combination with the spring A, pivoted at 80 *b*, having short arm *c* and long arm *d*, the latter provided with the thickened and curved end, strengthening-ribs *h*, and pin-hole *e*, as and for the purpose set forth.

2. A draw-head having the flaring mouth, 85 and recessed as described, in combination with the pivoted double-armed spring having one arm ribbed and thickened, and provided with the slot *e*, as described and specified.

In testimony whereof I have affixed my signature in presence of two witnesses.

ALEX. STORY.
